Des. 186,759
Patented Dec. 1, 1959

186,759

BASEBALL SAFETY HELMET

Edwin R. Crick, Jr., Chesterland, Ohio, assignor to American Baseball Cap, Inc., Pittsburgh, Pa., a corporation of Pennsylvania

Application April 14, 1958, Serial No. 50,462

Term of patent 14 years

(Cl. D3—13)

I claim:

The ornamental design for a baseball safety helmet, as shown.
